UNITED STATES PATENT OFFICE.

FRED W. LEUTHESSE, OF CHICAGO, ILLINOIS.

AIR-VALVE FOR RADIATORS.

1,042,012.

Specification of Letters Patent. Patented Oct. 22, 1912.

Application filed December 20, 1911. Serial No. 666,929.

To all whom it may concern:

Be it known that I, FRED W. LEUTHESSE, a citizen of the United States, residing at Chicago, in the county of Cook and State of Illinois, have invented certain new and useful Improvements in Air-Valves for Radiators, of which the following is a specification.

The present invention relates to that type of air valve which employs a thermostatic member, commonly termed an expansion post, for regulating the escapement of air from the radiator.

The principal objects of the present invention are to eliminate the separable member which is usually provided for the purpose of forming a lower abutment for the expansion post; to eliminate the configuring of the interior of the valve casing for the purpose of providing an abutment for the lower end of the expansion post; and to provide an abutment for said lower end of the expansion post in a manner different from those above enumerated.

The invention further relates to the features of construction and to the combination of parts hereinafter described and claimed.

In the drawings, Figure 1 is a longitudinal section of an air valve constructed in accordance with the present invention; Fig. 2, a view similar to Fig. 1, showing the expansion post and the nipple which is secured to the upper end of the return pipe, in elevation; and Fig. 3, a view similar to Fig. 2, showing a modified form of upper abutment for the expansion post.

In the art to which the present invention relates, it is customary to employ a member known as an expansion post, which is susceptible to thermal changes; and this expansion post is located in the interior of the valve casing and lies between upper and lower abutments. It has heretofore been customary, so far as I am aware, to either form a separable piece which provides an abutment for the lower end of the expansion post, or to configure the interior of the casing so as to have a portion of its inner walls provide said abutment. In the present invention, the abutment is formed in a manner different from either of the two methods heretofore described.

Referring to Fig. 1, the device comprises a casing 4, provided with the ordinary nipple 5, adapted to be attached to the radiator;

and the casing is further provided with the usual cap-piece 6 screw-threaded to its upper end. Screw-threaded to the lower end of the casing is a coupling or union nut 7, which connects a nipple or collar 8 with the 60 casing. Said nipple or collar is adapted to be secured to the upper end of the return pipe, and when the valve is placed in operative position, this nipple becomes, in fact, the upper end of the return pipe, since it 65 is locked thereto. The upper end of the nipple, as will be clearly seen from Fig. 1, is configured to provide an inwardly tapered opening 9, which forms a seat or abutment for the locked end 10 of an expansion post 70 11. It will be seen from the drawings that the expansion post is in a free condition within the casing; that is, it is not positively attached to any other portion of the valve mechanism.

It will, of course, be understood that the upper end of the nipple is shown as being provided with an inwardly tapered end, because of the fact that the expansion post in the form illustrated has its ends of a tapering configuration. The particular configuration of the upper end of the nipple and the lower end of the expansion post shown is not the only form which could be employed in carrying out the present invention. It may be stated, as a general fact, that the upper end of the nipple must be configured in correspondence to the configuration of the lower end of the expansion post, at least in such a manner as to give a 80 substantially firm and rigid bearing for said lower end. The upper end 12 of the expansion post is adapted to seat against a ring 13; and the expansion post recedes and advances from this ring 13 to control the 85 escapement of air from the radiators, as is well known by those skilled in the art. 90

In Fig. 3 the construction is exactly similar to that shown in Fig. 1, save that the ring 13, in place of being open at its upper 100 end, is closed by a web 16. By providing an abutment for the lower end of the expansion post in the manner described, the separate part which is commonly employed for such abutment is entirely dispensed with, and, moreover, the expansion post is so positioned within the casing as to enable it to be readily removed through the lower end of the casing—a feature which is difficult, if not impossible, when the inner por- 110

tion of the casing is of a configuration to provide an abutment for the lower end of the expansion member.

I claim:

- 5 1. In an air valve for radiators, the combination of a casing provided with an inlet for connecting it to the radiator, an expandable member loosely held within the casing, an upper abutment adjustable in and detachable from the casing, and having a seating face for the upper end of the expandable member, a freely detachable coupling nipple having an opening therein contracted intermediate its ends, the wall below said contraction being screw-threaded, the wall above said contraction being configured to provide a seating face for the lower end of the expandable member and furnishing a lower abutment for the expandable member,
- 10 20 said member being separated and loosely held in position between the seating faces of the upper and lower abutments, the lower open end of the valve casing being of a size to permit the expandable member to pass freely therethrough, a coupling nut for attaching the nipple to the casing, the upper and outer edge of the nipple bearing against the lower inner edge of the open lower end of the casing making a steam and air tight joint at this point, substantially as described.
- 15 25 30 2. In an air valve for radiators, the com-

bination of a casing provided with an inlet for connecting it to a radiator, an expandable member loosely held within the casing, an upper abutment adjustable in and detachable from the casing and having a seating face for the upper end of the expandable member, a freely detachable coupling nipple having an opening therethrough contracted intermediate its ends, the wall of 40 said opening below said contraction being screw-threaded, the wall of said opening above said contraction being configured to provide an outwardly flaring funnel-shaped opening providing a seat for the lower end 45 of the expandable member and furnishing a lower abutment for the expandable member, said member being supported and loosely held in position between the seating faces of the upper and lower abutments, the 50 lower open end of the valve casing being of a size to permit the expandable member to pass freely therethrough, a coupling nut for attaching the nipple to the casing, the upper outer edge of the nipple bearing against 55 the lower inner edge of the open lower end of the casing making a steam tight joint at this point; substantially as described.

FRED W. LEUTHESER.
